CAR TRUCK.

APPLICATION FILED NOV. 25, 1913.

Patented Mar. 9, 1915.

2 SHEETS—SHEET 2.

UNITED STATES PATENT OFFICE.

HERBERT H. HEWITT, OF BUFFALO, NEW YORK.

CAR-TRUCK.

1,130,730.

Specification of Letters Patent. Patented Mar. 9, 1915.

Application filed November 25, 1913. Serial No. 302,872.

To all whom it may concern:

Be it known that I, HERBERT H. HEWITT, a citizen of the United States, and a resident of Buffalo, county of Erie, and State 5 of New York, have invented certain new and useful Improvements in Car-Trucks, of which the following is a full, clear, and exact description.

The present improvement relates to car 10 trucks and more particularly to car trucks in which the supporting springs are interposed between the journal boxes and the truck frame.

The invention seeks to provide an improved truck of this type in which the construction permits the rocking movement of the side frames and wheel axles, so that the wheels of the truck are free to rise and fall independently in passing over irregularities in the track without straining or distorting the parts of the truck.

The invention consists in the features of construction hereinabove set forth, illustrated in the preferred form in the accompanying drawings and more particularly pointed out in the appended claims.

In the drawings, Figure 1 is a plan view of a half portion of the improved truck with one of the side frames shown in horizontal section. Fig. 2 is a view in elevation with a portion of the side frame and one of the journal boxes shown in vertical section. Fig. 3 is a cross-section, with the truck side frames and one-half of the connecting member or bolster shown in section on the line 3 of Fig. 1. Fig. 4 is a detail end view of one of the side frames illustrating the manner of mounting the journal box thereon. Fig. 5 is a detail section on the line 5-5 of Fig. 2. Fig. 6 is a detail section of the truck transom taken on the line 6-6 of Fig. 3.

In the present improved construction, the car-supporting center and side bearings are 45 mounted directly upon the transverse connecting member or bolster of the truck, and the side frames are pivotally and removably connected to the ends of the truck bolster that carries the center and side bearings, so that the side frames are free to rock in longitudinal, vertical planes.

In the preferred embodiment of the invention illustrated, each side frame comprises an enlarged central portion 10, pairs 55 of inclined converging side arms 11 which

extend from the upper and lower parts of the central portion and which are connected at their outer ends by pedestal yokes 12. These parts are preferably formed of an integral casting, and the central portion 10 and converging side arms 11 comprise a central web having wide, outer, marginal flanges 13 and narrow, inner, marginal flanges 14, and which flanges merge into the inner side walls of the pedestal yokes. 60 The central portion of each side frame is provided with an enlarged circular opening provided with an edge flange which, like the marginal flanges 13 and 14, projects in opposite directions from the central web of the side frame, and which forms an enlarged, transverse, cylindrical bearing 15. The cylindrical bearing flange 15 is slightly wider than the outer marginal flanges 13 and is connected thereto by radial bracing flanges 16.

The transverse connecting member or truck bolster 17 is preferably formed of an integral, hollow casting substantially rectangular in section and having top, bottom and side walls (see Fig. 3) which, for the sake of lightness, are provided with flanged openings 18. The car-supporting center and side bearings 19 and 20 are mounted directly upon the truck bolster 17 and are 70 preferably cast integral therewith. Vertical strengthening flanges 21 extend between the top and bottom walls of the truck bolster beneath the center and side bearings. The ends of the truck bolster are larger 75 transversely than the central portion thereof (see Fig. 1) and are provided with hollow, enlarged, cylindrical trunnions or journals 22 which are arranged to fit within the central cylindrical bearings 15 of the 80 side frames. On opposite sides of the central bearing, the side frames are provided with bosses 23 having pockets for receiving keys 24. These keys are removably held in place by pins or bolts 25 and the inner ends of the keys extend through vertical slots 26 formed in the walls of the hollow trunnions or journals 22 of the truck 85 transom. The side frames are thus removably connected to the ends of the truck transom and, inasmuch as the slots 26 are slightly wider than the keys 24, the side frames are free to rock independently to a limited extent in longitudinal, vertical 90 planes.

The side portions of the truck transom (see Fig. 3) are slightly inclined outwardly and downwardly from the central portion thereof, and the end trunnions are downwardly offset, so that the truck transom, upon which the car body is supported, forms an arch-like connecting member between the side frames of the truck. The inner ends of the journals or trunnions 22 are strengthened by internal circular flanges 27 and external flanges 28. The latter, which merge into the upper portion of the transom, form shoulders that abut against the inner faces of the side frames. Preferably, the latter are provided with a series of integral bosses 29 about the inner portion of the cylindrical bearing flanges 15, and against which the shoulders or flanges 28 abut, these bosses forming broad bearing surfaces to take the end thrust between the connected parts.

The walls of the pedestal yokes at the ends of each side frame are arranged in planes transverse to the plane of the side frame and are strengthened by vertical web flanges 30 which extend upwardly and outwardly over the pedestal yokes and downwardly to the outer lower end portions thereof. The lower ends of the yokes are open and their closed upper ends are circular and provided with depending flanges to form spring seats 31 (see Figs. 1, 2 and 5). Small, inclined, strengthening flanges 32 extend between the upper face of each spring seat 31 and the vertical web flange 30. The lower open ends of the pedestal yokes are closed and strengthened by spacing sleeves 33 and bolts 34.

The wheel axles 35 are provided with wheels 36 fixed thereto and projecting end journals 37 which are arranged within journal boxes 38. The general construction of the journal boxes is similar to the standard prescribed by the Master Car Builders' Association, each box having a suitable bearing or brass 39 for engaging the car axle journal 37. In the construction shown, the walls of the box are integral and the thickened top wall is provided on its lower face with an angular seat that directly engages the upper angular face of the bearing or brass 35. At the inner end of the seat, the top wall of the box is provided with a recess for receiving the upstanding flange 40 on the inner end of the brass. Inasmuch as the box is mounted so that it can rock in a transverse vertical plane, the bearing or brass can be inserted and removed without employing the usual fastening key.

The journal boxes are vertically guided in the pedestal yokes 12 at the ends of the truck side frames. For this purpose, the opposite side walls thereof are provided with vertical guide lugs 41 which overlap the side edges of the pedestal yokes. The supporting springs are interposed between the

journal boxes and the side frames and, in the preferred form shown, springs 42 are arranged between the spring seats 31 at the upper ends of the bearing yokes and spring supports 43 which rest upon the journal boxes. These spring supports, as most clearly shown in Fig. 1, are provided with guide lugs 44 which overlap the side edges of the vertical walls of the pedestal yokes.

The engaging parts of the journal boxes, pedestal yokes and spring supports are arranged to permit the free rocking movement of the journal boxes and wheel axles in transverse vertical planes. For this purpose, the thickened wall of each journal box is provided with a rounded bearing surface 45 and each spring support 43 is provided with a correspondingly shaped seat 46 for engaging this bearing surface. Preferably, these bearing surfaces are cylindrical and have a common, horizontal axis adjacent the axis of the journal and journal box at right angles thereto. It should be noted that the cylindrical bearing surface 45 on the upper portion of the journal box is considerably longer than the seat 46 formed in the spring support 43, so that the latter is carried upon the upper portion of this bearing surface and in such a manner that it will not interfere with the rocking movement of the box. The guide lugs 41 on the sides of the box are also cut away so that they will not interfere with the rocking movement of the box. In the preferred form shown, the inner side walls of these lugs diverge from the central portions thereof toward their ends, as most clearly shown in Fig. 4.

The improved truck construction is extremely strong, but at the same time is flexible to permit the independent movement of the wheel axles and wheels, so that they rest solidly on the track in passing over irregularities thereof without distorting or straining the parts of the truck. By reason of this construction, the shocks and strains transmitted to the journal bearings, the parts of the truck and the car body carried thereby are reduced. The free rocking movement of the journal boxes and wheel axles maintain the bearings accurately in line and eccentric wear thereon is avoided.

It should be noted that the enlarged central portion of the side frames is provided with the enlarged cylindrical bearings, and the enlarged end journals or trunnions of the truck transom afford ample strong bearings upon which the side frames are free to rock. It should be further noted that the axis of these bearings lies substantially in the same plane as the axes of the wheel axles. This arrangement permits of the distribution of the metal in the side frames which will give the maximum amount of strength with the minimum amount of weight. The arch-like construction of the

- truck bolster upon which the car supporting center and side bearings are directly mounted and upon which the ends of the side frames are swiveled, also aids in providing an effective strong construction. The side frames are removably mounted upon the journal ends of the truck transom, and the parts of the truck are otherwise so constructed that they may be readily assembled and taken apart for repairs and the like.
- It is obvious that numerous changes may be made in the details set forth without departure from the essentials of the invention as defined in the claims.
- I claim as my invention:—
1. A car truck comprising wheels and wheel axles, boxes for receiving the journals of said wheel axles, side frames having pedestal yokes at their ends wherein said boxes are vertically guided, supporting springs interposed between the tops of said boxes and the upper ends of said yokes, said side frames having enlarged, central, cylindrical bearing openings substantially in line with said car axles, a transverse connecting member having car-supporting center and side bearings and provided with end journals arranged within the bearing openings of said side frames, and means for detachably connecting said side frames to said journals in a manner permitting the independent rocking movement of said side frames, substantially as described.
  2. A car truck comprising parallel side frames having pedestal yokes at their ends, journal boxes vertically guided in said yokes, supporting springs interposed between the tops of said journal boxes and the upper ends of said yokes, and a truck bolster having car-supporting center and side bearings directly mounted thereon and provided with end journals, said side frames being removably mounted on the end journals of said bolster in manner permitting the limited rocking movement thereof in vertical planes, substantially as described.
  3. A car truck comprising parallel side frames having pedestal yokes at their ends, journal boxes vertically guided in said yokes, supporting springs interposed between the tops of said journal boxes and the upper ends of said yokes, said side frames having central, cylindrical, bearing openings, and a cast metal truck bolster having integral car-supporting center and side bearings, and integral end journals arranged within the bearing openings of said side frames and removably connected thereto, substantially as described.
  4. A car truck comprising side frames having pedestal yokes at their ends and enlarged, central, bearing openings, journal boxes vertically guided in said yokes, supporting springs interposed between the tops of said boxes and the upper ends of said
- yokes, a truck bolster of metal provided with car-supporting center and side bearings directly mounted thereon and having integral, hollow end journals extending into said bearing openings and shoulders at the inner ends of said journals bearing against the inner faces of said side frames, and removable keys extending transversely through the walls of said bearing openings and said journals for detachably connecting said side frame to said bolster in a manner permitting the limited rocking movement of said side frames, substantially as described.
5. A car truck comprising side frames having pedestal yokes at their ends and enlarged, central bearing openings, journal boxes vertically guided in said yokes, supporting springs interposed between the tops of said boxes and the upper ends of said yokes, a truck bolster of metal provided with car-supporting center and side bearings directly mounted thereon, and having enlarged, cylindrical, hollow ends journaled in the bearing openings of said side frames and flanges at the inner ends of said cylindrical ends bearing against the inner faces of said side frames, and means for detachably connecting said bolster and said side frames in a manner permitting the independent limited rocking movement of the latter in vertical planes, substantially as described.
6. A truck bolster formed of metal and having integral center and side bearings and integral, hollow end journals for engagement with bearing openings of the truck side frames, substantially as described.
7. In a car truck, parallel, metal side frames each comprising a central portion provided with a flanged cylindrical bearing opening, integral upper and lower side arms and integral pedestal yokes connecting the ends of said side arms, journal boxes vertically guided in said yokes, supporting springs interposed between the tops of said boxes and the upper ends of said yokes, and a truck bolster having cylindrical ends journaled in the openings of said side frames and removably connected thereto, substantially as described.
8. A cast metal side frame for car trucks comprising a flanged web and having an enlarged, flanged, central bearing opening midway between its upper and lower edges thereof for receiving the journal end of a transverse connecting member and integral pedestal yokes at its ends, substantially as described.
9. A car truck side frame comprising an enlarged central portion provided with a flanged, cylindrical bearing opening, integral, converging upper and lower side arms extending from said central portion, and integral pedestal yokes connected to the ends of said side arms, said central portion

and said arms being formed of a flanged web, and vertical web flanges extending over said yokes, substantially as described.

10. A car truck comprising an integral 5 metal truck bolster provided with car supporting center and side bearings and having enlarged, end journals with flanges at the inner ends of said journals, integral metal side frames having pedestal yokes at their 10 ends and enlarged central bearing openings substantially midway between their upper and lower edges for receiving said journals, means detachably connecting said side frames to said bolster, journal boxes vertically guided in said yokes, and supporting springs interposed between the tops of said boxes and the upper ends of said yokes, substantially as described.

11. A car truck comprising side frames 20 having pedestal yokes, a transverse connecting member provided with car supporting means and whereon said side frames are mounted to rock independently in vertical planes, car-axle journal boxes vertically 25 guided in said yokes and free to rock therein in transverse vertical planes, and supporting springs interposed between said journal boxes and said side frames, substantially as described.

30 12. A car truck comprising side frames having pedestal yokes at their ends, a transverse connecting member having car-supporting center and side bearings, and whereon said side frames are removably mounted 35 in a manner permitting the independent rocking movement thereof in vertical planes, car axle journal boxes and supporting springs mounted within the pedestal yokes of said side frames in a manner permitting 40 the rocking movement of said journal boxes in transverse vertical planes, substantially as described.

13. A car truck comprising side frames 45 having pedestal yokes, a transverse connecting member provided with car supporting means and whereon said side frames are mounted to rock independently in vertical planes, car-axle journal boxes and spring supports, vertical guides in said pedestal 50 yokes, said spring supports being mounted on said boxes, and springs interposed be-

tween said supports and the upper ends of said yokes, the engaging parts of said boxes, yokes and spring supports being arranged to permit the transverse rocking movement 55 of said boxes, substantially as described.

14. In a car truck, the combination of connected side frames having pedestal yokes at their ends, wheels and wheel axles, journal boxes for said wheel axles, means for retaining said journal boxes in said yokes, arranged to permit the vertical movement and the free transverse rocking movement of said journal boxes with respect to said yokes, and supporting springs interposed 60 directly between said boxes and said side frames, substantially as described.

15. In a car truck, the combination of a side frame having pedestal yokes, journal boxes and spring supports vertically guided 70 in said yokes, said supports being mounted on said boxes, and springs interposed between said supports and the side frame of the engaging parts of said boxes, yokes and spring supports being arranged to permit 75 the transverse rocking movement of said boxes, substantially as described.

16. In a car truck, the combination of a side frame having pedestal yokes, journal boxes vertically guided in said yokes in a 80 manner permitting the transverse rocking movement thereof, said boxes having rounded upper surfaces, spring supports mounted on the rounded upper surface of said boxes and vertically guided in said yokes, and 85 springs interposed between said supports and the truck side frame, substantially as described.

17. In a car truck, the combination of a side frame having pedestal yokes, journal 90 boxes and spring supports vertically guided in said pedestal yokes, said boxes having cylindrical, convex, upper faces, and said spring supports having cooperating, cylindrical, concave seats to permit the trans- 95 verse rocking movement of said boxes, substantially as described.
